UNITED STATES PATENT OFFICE

2,552,808

SUPPORTING DEVICE FOR PIPE CLEANING MACHINES

John V. O'Brien, Park Ridge, Ill.

Application March 11, 1947, Serial No. 733,810

7 Claims. (Cl. 15—104.3)

1

The invention relates generally to improvements in machines for use in cleaning pipes of various kinds, and removing stoppages in drains, such as sink drains, floor drains, etc., but relates more particularly to portable machines for this purpose.

The general object of the invention is to provide a machine of this kind which shall be light, compact and sturdy so that it may be easily carried and operated by one man and which at the same time shall function efficiently for a variety of purposes, such as cleaning out scale, corrosion and stoppages in drains and pipes.

Another object of the invention is to provide a machine of this kind having a motor for actuating the flexible cable, to which the cutter element is attached, and an associated drum for storing the unused portion of the cable, the motor in non-operative position being supported closely adjacent the drum so that the drum and motor may be transported as a unit, and the motor being easily withdrawn with sufficient cable as necessary for use in the cleaning of pipes, drains and the like.

Again it is an object of the invention to provide a flexible cable storage drum and stand for supporting the drum, so that the drum may freely rotate on one axis in response to torque developed in the cable by the power unit in a cleaning operation and which drum is trunnioned on a horizontal axis to enable the drum to be swung to the position best adapted to permit the cable to pass from the drum to and through the power unit during a cleaning operation.

Other objects and advantages of the invention will appear as I proceed with a description of the invention in connection with the accompanying drawing in which

Fig. 1 is a perspective view of a pipe cleaning machine embodying my invention, the parts being in the non-operative position they occupy when the device is ready to be stored or transported.

Fig. 2 is a top plan view of the machine, but with the motor removed, as when used and the motor supporting arm swung downwardly into a position of rest against the top of the drum supporting cradle.

Fig. 3 is a detail sectional view on the line 3—3 of Fig. 2.

Fig. 4 is a view of the machine in elevation, certain of the parts being broken away to disclose the interior construction and only a portion of the handle of the power unit being shown, and

2

Fig. 5 is a view, at right angles to Fig. 4, showing the drum tilted at an angle, being one of a number of positions in which it may be placed to facilitate use.

5 The machine comprises, as main parts, the stand 1, flexible cable containing drum 2, cradle 3, for supporting drum 2 in stand 1, and power unit 4 for rotating flexible cable 5.

The details of the reel and reel support are 10 claimed in my copending application Ser. No. 6,896, filed February 7, 1948.

The stand 1 comprises parallel angle iron members 6—6, which are held in spaced relation by a U-shaped metal band 7 having a base portion

15 8 and upstanding side leg portions 9—9. The U-shaped member 7 is permanently secured to the member 6—6 as by welding, or in any other suitable manner. The top portions of the legs 9—9 are preferably bent outwardly at right angles

20 and then reverse folded as shown at 10—10. There are thus provided parts which may serve as handles, if desired, although the machine as a whole may be conveniently carried in one hand, by grasping the top span of the cradle member 3

25 slightly at one side of center.

The cradle 3 is conveniently a casting comprising a bottom span portion 11, upstanding side portions 12—12 and top portions 13—13, which extend upwardly and inwardly and which merge into an integral offset central portion 15.

Associated with the offset portion 15 is a plate 16, which is bowed outwardly so that a spherical portion 17 of a brass bearing 18, which is positioned in the top of the drum along the axis of rotation of the drum, may be clamped between said parts. There is thus provided a self-aligning bearing for the upper part of the drum.

The lower part of the drum is supported upon an anti-friction bearing carried in the central part of the lower span 11 of the cradle 3. As shown the anti-friction bearing comprises a ball bearing 19, which is accommodated in an opening in the span 11, being supported by a plate 20 bolted to the under side of the span 11.

45 The bottom wall of the drum carries a stud 21 having a reduced portion 22, which engages the center ring of the anti-friction bearing and a reduced and threaded upper portion 23, which extends into the interior of the drum. On the bottom outside surface of the drum is a reinforcing plate 24 and on the inner surface is a washer

50 25. By means of nut 26, the stud 21 is held firmly in position, the washer 25 and reinforcing plate 24 being pressed firmly against the respective sides of the drum bottom.

By the means described, the drum is positioned for free rotation in the cradle 3 in response to torque imparted to the flexible cable 5 when rotated by the power unit 4.

In the operation of the machine, it is convenient to have the axis of rotation of the drum in a position other than vertical for which reason the cradle is mounted so that it may be swung or tilted to the desired position, one such position being shown in Fig. 5. For this purpose there is provided a bolt 27 at each side of the stand. The bolts 27 pass through openings in the legs 9-9 and have threaded engagement with a tapped hole in the adjacent portion of each cradle side portion (see Fig. 3). A washer 28 is provided under the head of the bolt. These bolts are drawn up just tight enough to permit the cradle to be swung to the desired position, but so that the cradle, and drum carried thereby, will remain in any placed position.

The power unit 4 comprises a motor 30 having a gear housing 31 at one end and a hollow handle portion 32 at the opposite end. Extending from the gear casing end of the power unit is a chuck 33 through which the flexible cable 5 passes and by means of which the actuation of the cable by the power unit may be controlled. At that end of the cable external to the drum there is secured a suitable tool 34 for cutting away the scale, corrosion, or other material causing the stoppage or restriction in the pipe, drain, etc.

When the parts are in their non-operative position (see Figs. 1 and 4) the lower hollow portion of the handle 32 telescopes over the upper cylindrical end of the bearing 18, thus serving to support one end of the power unit. The other end of the power unit is supported by a swingable arm 35 pivoted to the cradle as at 36 and having a saddle-like portion 37 at its outer end in which the lower part of the power unit rests, while engaged with shoulder 40 of the gear housing. A projection 38, on the cradle, serves as a stop to limit movement of the arm 35 in one direction. When the power unit is functioning the arm 35 is swung downwardly to the position shown in Fig. 2.

Current to energize the motor 30 of the power unit is supplied by means of the conventional conductor 39, which may be plugged into any convenient electrical outlet.

When the parts are in the position shown in Fig. 1, the entire machine may be conveniently transported by gripping one side of the upper portion of the saddle with one hand, preferably on that side over which the power unit extends. Because of the compact arrangement, the machine can be carried into rather confined quarters and positioned conveniently adjacent the outlet of the pipe, drain or the like to be cleaned. It will be understood at this time that the major part of the flexible cable is stored in coiled condition within the storage drum, where it is out of the way.

Operation

Assuming the machine has been placed adjacent the pipe or drain to be cleaned, the power unit is lifted away from the stand, cradle, and drum, at the same time pulling a portion of the cable from the drum through the hollow upper bearing 18. Before starting the actual cleaning operation, the cradle will be positioned at that angle which will move the drum so that its axis of rotation will most freely permit of the paying out of the flexible cable. The tool at the end

of the flexible cable is then inserted in the pipe or drain opening and the motor started to cause rotation of the cable and the cutter affixed thereto. The cable is then fed forward as the cleaning operation progresses.

When the cleaning operation has been completed, the parts may be quickly and easily restored to the position shown in Fig. 1. The soiled cable is then stored within the drum, where it may be dried, aerated, and cleaned, if desired, through the vent holes 41.

The apparatus is at once light, compact, sturdy and efficient for its intended purpose.

While I have illustrated and described the preferred form of the invention as required by law, I do not wish to be limited to the specific details, except as may be necessary by limitations in the hereunto appended claims.

I claim as my invention:

1. A pipe cleaning machine embodying therein a flexible cable holding drum, a supporting structure for the drum and including parts above and below said drum and in which it is journalled for rotation, a tubular member projecting beyond said part of the supporting structure above the drum and communicating with the interior thereof and forming a cable payout opening therefore, mechanisms through which said cable extends and operative for imparting rotation to said cable, and including a part removably fitting upon said tubular member and forming, one part of the support therefor, and means carried by said structure laterally of said tubular member and engageable by another part of said mechanism and forming a second part of the support therefor.

2. A pipe cleaning machine embodying therein a flexible cable holding drum, a supporting structure for the drum and including parts above and below said drum and in which it is journalled for rotation, a tubular member projecting beyond said part of the supporting structure above said drum and communicating with the interior thereof and forming a cable payout opening therefore, and an electric motor driven mechanism for imparting rotation to said cable and including a hollow handle portion that has removable telescopic engagement with said tubular member and forming, at least, a part of the support of said mechanism.

3. A pipe cleaning machine embodying therein a flexible cable holding drum, a supporting structure for the drum and including parts above and below said drum and in which it is journalled for rotation, a tubular member projecting beyond said part of the supporting structure above said drum and communicating with the interior thereof and forming a cable payout opening therefore, an electric motor driven mechanism for imparting rotation to said cable and including a casing and a hollow handle portion through which said cable extends and which handle portion has removable telescopic engagement with said tubular member and forming, at least, a part of the support for said mechanism, and an arm swingably mounted on said part of the supporting structure above the drum and engageable with said casing and forming the other part of the support for said mechanism.

4. A pipe cleaning machine embodying therein a flexible cable holding drum, a supporting structure for the drum and including parts above and below said drum, means providing a bearing engagement for the bottom of the drum with said part of the structure below the same, a

tubular member projecting from the top of said drum and journalled in and extending beyond that part of the supporting structure above said drum and communicating with the interior of the drum and forming the payout opening for the cable therein, and mechanism for imparting rotation to said cable and including a portion through which said cable extends and which portion has removable telescopic supporting engagement with the projecting part of the tubular member.

5. A pipe cleaning machine embodying there-in a stand, a flexible cable holding drum mounted for rotation on said stand and including a tubular part journalled in a part of said stand and forming a cable payout opening for said drum, mechanism having a hollow part through which said cable extends and operative for imparting rotation to said cable, said hollow part of said mechanism being adapted for detachable telescopic engagement with said tubular part while having supporting bearing engagement upon said part of said stand between uses of said cable.

6. A pipe cleaning machine embodying there-in a stand, a flexible cable holding drum mounted for rotation on said stand, said drum including a tubular part journalled in a part of the stand and forming a cable payout opening of said drum, mechanism through which said cable extends and operative for imparting rotation to the flexible cable during use thereof, said mechanism including a part adapted for telescopic engagement with said tubular part, and an arm carried by said stand and engageable by another part of said mechanism for supporting said mechanism upon the stand in a position extend-

10 ing laterally from said tubular member between uses of said cable.

7. A pipe cleaning machine embodying there-in a stand, a flexible cable holding drum, means mounting said drum for rotation on the stand and including a tubular part forming a cable payout opening for the drum, a power unit for imparting rotation to said cable, said unit having a hollow handle portion through which said cable passes, and which is telescopically engageable with said tubular part for supporting one end of said power unit when it is in an inoperative position between uses of the cable.
